WORKPIECE SUPPLY FIXTURE FOR INDUCTION HEATING APPARATUS

William B. Albrecht, Wauwauosa, Wis., assignor to Allis-Chalmers Manufacturing Company, Milwaukee, Wis.

Application June 5, 1953, Serial No. 359,744

9 Claims. (Cl. 219—10.69)

This invention relates in general to induction heating apparatus and more specifically to an improved fixture for automatically supplying workpieces to the heating station in a consecutive manner.

The heat treating of various kinds of objects by a high frequency current is well known and has proved successful in producing therein desired metallurgical characteristics. The object to be heated, commonly referred to as the workpiece, is positioned in a heating station, defined by a portion of an induction heating work coil, for a predetermined period of time, depending on the size and shape of the workpiece and the heat treating operation being performed.

In some suggested apparatus the work coil which defines the heating station comprises a hairpin like inductor, the workpieces passing through the inductor in a direction parallel to the lengthwise direction of the inductor while they are being heated. In other suggested apparatus the work coil comprises a number of conductor turns which define a vertical passage, the workpieces being positioned in the passage so that the conductor turns substantially surround it during the heating cycle. Of the two types of work coils it has been found that the workpiece is heated more uniformly when it is substantially surrounded by the work coil.

Previously suggested induction heating apparatus which utilized a work coil that substantially surrounds the workpiece have not proved satisfactory for some types of heat treating operations. Specifically, in annealing thin wall cylindrically shaped workpieces, such as shell castings where the time required to heat the workpiece is relatively short, the apparatus does not supply workpieces to the work coil with sufficient speed to operate efficiently.

To overcome this disadvantage it is proposed, according to the present invention, to provide an improved induction heating apparatus which includes a fixture for positioning workpieces rapidly in the heating station. This fixture comprises a pair of substantially parallel flat movable plates disposed transverse to and on opposite ends of the heating station. One plate provides a support for the workpiece in the station and the other plate provides a support for the workpieces to be positioned in the station. The plates cooperate with each other on being moved to allow the workpieces to be fed by gravity to the heating station in a consecutive manner. In addition to supporting the workpiece in the heating station the lower plate provides means for rotating the workpiece to insure an even distribution of heat.

It is therefore an object of the present invention to provide an improved induction heating apparatus for heat treating workpieces in a consecutive manner.

Another object of the present invention is to provide an improved induction heat treating apparatus which includes a fixture for simultaneously supplying workpieces in a consecutive manner to a plurality of heating stations.

A further object of the present invention is to provide an improved induction heating apparatus including a fixture which automatically positions the workpiece in the

2

heating station and rotates the workpiece while it is being heated.

A still further object of the present invention is to provide an induction heating apparatus for consecutively annealing a plurality of thin wall cylindrical workpieces, the apparatus including a fixture having a pair of movable members which cooperate with each other to allow the workpieces to be positioned rapidly by gravity in the heating station in a consecutive manner.

Objects and advantages other than those mentioned above will become apparent from the following description when read in connection with the drawings in which:

Fig. 1 is a front view partly in section of the induction heating apparatus embodying the present invention;

Fig. 2 is a partial plan view of the apparatus shown in Fig. 1; and

Figs. 3 and 4 are schematic views of the apparatus shown in Fig. 1.

The apparatus shown in Fig. 1 comprises generally a source of high frequency current shown schematically as a generator 12 which is connected to an induction heating work coil 13 for heat treating workpieces being supplied to work coil 13 by fixture 14.

Generator 12 and work coil 13 may be of any suitable type known in the art. As shown, work coil 13 comprises a plurality of flat plate inductors 17, 18 and 19 which are disposed in parallel spaced relationship with each other and which are connected together electrically by cooling conduit 20 in a suitable manner. The inductors 30 are provided with two cylindrical openings each, which form two passages 21 and 22 when the inductors are assembled with corresponding openings in axial alignment.

Fixture 14, which operates to position workpieces automatically in passages 21 and 22, comprises a frame having a base 23 and a panel 24 disposed substantially perpendicular to base 23 and secured thereto by braces 26, 27. A shelf 28, disposed parallel to base 23 and rigidly secured to panel 24 in a suitable manner, serves to support a holding device 29 and a control switch 30 for generator 12. A centrifugal switch 31 is mounted on a top flange 25 positioned above shelf 28. Device 29 and switches 30 and 31 are all actuated by rotation of shaft 32 whose axis of rotation is parallel to the axes of passages 21 and 22 of work coil 13 and is spaced from each axis a predetermined distance. Shaft 32 is suitably journaled in portion 33 of bracket 34, which is rigidly bolted to panel 24.

Shaft 32 may be actuated by any suitable known means to cause it to either rotate or oscillate about its axis. In the preferred embodiment of the apparatus, shaft 32 is rotated about its axis by means of a variable speed motor 36 which has its shaft 37 connected to shaft 32 through a spring biased slip clutch 38.

A plate 39 is disposed on shaft 32 immediately below shelf 28 and is fixedly attached to shaft 32 by a key 41. Plate 39 when suitably moved to one position operates to support two columns of workpieces which are stacked in vertically disposed guide tubes 48 and 49, portions of 60 which are shown in Fig. 1, and when plate 39 is moved to another position it is inoperable to support the workpieces. Guide tubes 48 and 49 are positioned above passages 21 and 22, respectively, of work coil 13 and aligned therewith so that the columns of workpieces rest on plate 39, the columns extending upward through openings 51, 52 in holding device 29 into guide tubes 48, 49 which are attached to device 29. In order to allow workpieces to be supplied to the heating station by gravity plate 39 is provided with an opening through which the 65 lowermost workpieces may pass when the plate is suitably actuated. If desired a plurality of such openings may be provided in the plate, the openings being spaced

70

circumferentially with respect to each other. If the work coil has a plurality of heating stations the plate may also be provided with other openings which are in radial alignment with the circumferentially spaced openings. As shown in Fig. 3 plate 39 is substantially circular and is provided with two circumferentially elongated openings 42 and 43 which are disposed diametrically opposite each other and are located with their center lines an equal distance from the center of plate 39. Also since work coil 13 has two heating stations, the circumferential edge 44 of plate 39 is recessed radially inward opposite openings 42 and 43 to provide two other openings 46 and 47 which are radially aligned with openings 42, 43, respectively.

A second plate 53 is spaced axially below plate 39 on shaft 32 and fixedly attached to the latter by a set screw 54. Plate 53 is similar to plate 39 and operates to support the workpieces in passages 21 and 22 of work coil 13 during the heating cycle. As shown in Fig. 3 plate 53 differs from plate 39 in that it has two annular recesses 56 and 57. Recess 56 forms a pair of circular edges 58 on the upper face of plate 53 and recess 57 forms a like pair of edges 59. One edge of each pair lies on circles which are concentric with shaft 32 and pass through the axes of passages 21 and 22. When plate 53 is rotated recess 56 passes under only the half of passage 21 which is nearest the axis of rotation of shaft 32, the radius of one of the circular edges 58 being equal to the distance between the axes of shaft 32 and passage 21. Recess 57 is similarly positioned with respect to passage 22. Therefore, while the workpieces are being supported in passages 21, 22 by plate 53, only half of the workpieces are in contact with the plate at any one time, the other half extending over one of the annular recesses 56 or 57.

Disposed intermediate plate 39 and plate 53 is a U-shaped channel 61 which is secured to bracket 34 and which serves as a holding means for ceramic bushings 62. Ceramic bushings 62 are disposed on both ends of passages 21 and 22 of work coil 13 and are fitted into suitable recesses of channel 61. These bushings when axially aligned with passages 21 and 22 act as guides for centering the workpieces in the passages and for preventing the workpieces from coming in contact with any part of work coil 13.

Holding device 29 operates to hold each column of workpieces in a fixed position when plate 39 is rotated to a nonsupporting position, for example, when any of the openings in plate 39 are positioned below passages 51, 52 of device 29. Device 29 comprises an actuating arm 63 having one end pivotally attached to a pivot pin 64 secured to top flange 25, and the other end operable to hold the columns of workpieces stationary. Since the diameters of the workpieces may vary slightly means are provided to allow one column to be held with a force independent of the force on the other column. This holding action is obtained through spring 66 which biases arm 63 against cam 67 that is positioned on shaft 32 in a predetermined relationship with plate 39. The end of arm 63 which acts to clamp the second lowermost workpiece 68 of each column against the walls of openings 51 and 52, includes two pins 71 and 72 which bear against the workpieces 68 when arm 63 is in the holding position, pin 71 being rigidly fixed in arm 63 while pin 72 is biased by a spring 73. This arrangement allows the workpiece in each column to be held firmly because the holding force of pins 71, 72 are independent of each other. When plate 39 is in a position to support the column of workpieces, cam 67 opposes the biasing action of spring 66 and allows the workpieces to drop and rest on plate 39.

Control switch 30 is actuated by a cam 76 which is suitably positioned on shaft 32 to open switch 30 and cause work coil 13 to be energized when the workpieces are positioned in passages 21 and 22 of work coil 13.

Cam 76 is a butterfly type cam and may be adjusted to vary the time switch 30 remains in the open position. Likewise, centrifugal switch 31 is mounted on top flange 25 and suitably coupled to shaft 32 by a chain drive to prevent work coil 13 from being energized by switch 30 while shaft 32 is rotating below a predetermined speed.

The various electrical connections for the apparatus are shown in Figs. 3 and 4 which represent schematic views of the apparatus shown in Fig. 1. Motor 36 is connected to a suitable voltage supply circuit 79 through a manually operated switch 80. Generator 12 is also connected across circuit 79 through manually operated switch 81. Control switch 30 is connected to generator 12 through suitable control means 83, and centrifugal switch 31 is connected in shunt with switch 30. Control means 83 operates to cause work coil 13 to be energized from generator 12 only when both switches 30 and 31 are open.

The operation of the apparatus, shown in Fig. 1 in the deenergized position, is as follows. Switch 81 is moved to the closed position to energize generator 12, and switch 80 is moved to the closed position to energize motor 36 and cause shaft 32 to rotate clockwise, as shown in the drawings. Rotation of shaft 32 opens centrifugal switch 31 which allows the energizing of work coil 13 to be controlled by switch 30.

As shown in Fig. 1 the stacks of workpieces in guide tubes 48 and 49 are supported by plate 39 and remain supported by the plate until immediately before the openings 42 and 46 in plate 39 are positioned below passages 51 and 52 in device 29, at which time arm 63 is moved to the clamping position by action of biasing spring 66 and cam 67. Arm 63 when in the clamping position causes pins 71 and 72 to force the second lowermost workpiece 68 of each stack against the walls of passages 51 and 52 thereby holding the stack of workpieces in a stationary position. Arm 63 remains in this position as shaft 32 continues to rotate causing openings 42 and 46 of plate 39 to pass under passages 51 and 52 which allows the lowermost workpiece 89 in each stack to drop into passages 21 and 22.

Plate 53 is positioned on shaft 32 with its openings circumferentially offset from corresponding opening in plate 39 so that by the time the bottom of the workpieces 89 have reached the plane of plate 53, the latter is in a position to support workpieces 89 in passages 21 and 22. This condition is shown schematically in Fig. 3 where the workpieces 89 which were lowermost in each tube have fallen through the radially aligned openings 42 and 46 in plate 39 into passages 21 and 22. Cam 67 is shown about to actuate arm 63 to the nonclamping position and allow the stacks of workpieces to drop and be supported as before by plate 39. Control switch 30 as shown in Fig. 3 is actuated to the open position by cam 76 thus allowing work coil 13 to be energized from generator 12.

If desired, workpieces 89 presently positioned in passages 21 and 22 may be rotated about their respective axes by suitable means while being heated. As shown in Figs. 3 and 4 only one-half of the bottom of each workpiece 89 is in sliding contact with the plate at any one time because the other half extends over one of the annular recesses 56 or 57. Therefore, the friction between the bottom of the workpieces 68 and the portions of the plate adjacent the annular recesses 56, 57 causes each workpiece to be turned clockwise about its axis. To provide more rotation of the workpiece the coefficient of friction of the contacting portion may be increased in any suitable manner, such as by knurling the contacting portions or inlaying a piece of material having a higher coefficient of friction than the plate.

At the end of the heating cycle plate 53 has been rotated to a position so that openings 43 and 47 of plate 53 are passed under passages 21, 22 of work coil 13 to allow the heated workpieces to drop through these openings. This condition is shown schematically in Fig. 4 where

the heated workpieces are beginning to drop from passages 21 and 22, control switch 30 is then in the closed position and arm 63 has just been moved to the clamping position by cam 67 and spring 66. Further rotation of shaft 32 brings the plates to a position similar to that shown in Fig. 3, but with shaft 32 being rotated 180° so as to position openings 43 and 47 where openings 42 and 46 are positioned in Fig. 3. The operation is then repeated.

If for some reason plate 39 or plate 53 becomes jammed by a workpiece so that shaft 32 cannot rotate, clutch 38 allows motor shaft 37 to continue rotating. However, since centrifugal switch 31 which is actuated by rotation of shaft 32, is then closed, work coil 13 will not be energized and the danger of overheating a workpiece is eliminated.

The apparatus is shown in the drawings utilizing only one work coil that defines two heating stations. However, it will be apparent to one skilled in the art that a plurality of work coils may be used in spaced relationship with each other if desired, and it will also be apparent that the work coil may define one or more heating stations.

Although but one embodiment of the present invention has been illustrated and described, it will be apparent to one skilled in the art that various changes and modifications may be made therein without departing from the spirit of the invention or from the scope of the appended claims.

It is claimed and desired to secure by Letters Patent:

1. Apparatus for consecutively heat treating a plurality of workpieces by induction from a high frequency current, said apparatus comprising a work coil defining a heating station; means for positioning workpieces in said station in a consecutive manner comprising means disposed above said station for stacking said workpieces, a first movable member disposed above said station and below said stacking means, said first member being operable in one position to support the lowermost workpiece of said stacked workpieces and inoperable in another position, a second movable member disposed below said station, said second member operable in one position to support a workpiece in said station and inoperable in another position, mechanical means common to both members to move said members from said one position to said other position to cause said workpieces to be positioned in a consecutive manner by gravity in said heating station; means for energizing said work coil with a high frequency current and means to control said energizing means in a predetermined manner with respect to said positioning means.

2. Apparatus for consecutively heat treating a plurality of workpieces by induction from a high frequency current, said apparatus comprising a work coil defining a heating station; means for positioning workpieces in said station in a consecutive manner comprising means disposed above said station for stacking said workpieces, a first movable member disposed above said station and below said stacking means, said first member being operable in one position to support the lowermost workpiece of said stacked workpieces and inoperable in another position, a second movable member disposed below said station, said second member operable in one position to support a workpiece in said station and inoperable in another position, an actuating shaft connected to move said members from said one position to said other position to cause said workpieces to be positioned in a consecutive manner by gravity in said heating station, and means to move said shaft; means for energizing said work coil with a high frequency current and means to control said energizing means in a predetermined manner with respect to said positioning means.

3. Apparatus for consecutively heat treating a plurality of workpieces by induction from a high frequency current, said apparatus comprising a work coil having a

workpiece receiving passage; means for positioning workpieces in said passage in a consecutive manner, said positioning means including a fixture comprising an actuating shaft having its axis of rotation parallel to the axis of said workpiece receiving passage and spaced laterally therefrom a predetermined distance, means to rotate said shaft, a first plate disposed above said passage and fixedly attached to said shaft, a second plate disposed below said passage and fixedly attached to said shaft, each said plate having an opening disposed therein spaced radially from said axis of rotation of said shaft said predetermined distance, and means disposed above said first plate for stacking said workpieces along said axis of said passage with the lowermost workpiece in contact with said first plate, said plates being disposed on said shaft so as to cooperate with each other on rotation of said shaft to cause each said lowermost workpiece to be positioned consecutively in said passage; means to energize said work coil with a high frequency current; and means to control said energizing means in a predetermined manner with respect to said positioning means.

4. Apparatus for consecutively heat treating a plurality of workpieces by induction from a high frequency current, said apparatus comprising a work coil having a workpiece receiving passage; means for positioning workpieces in said passage in a consecutive manner, said positioning means including a fixture comprising an actuating shaft having its axis of rotation parallel to the axis of said workpiece receiving passage and spaced laterally therefrom a predetermined distance, means to rotate said shaft, a first plate disposed above said passage and fixedly attached to said shaft, a second plate disposed below said passage and fixedly attached to said shaft, each said plate having an opening disposed therein spaced radially from said axis of rotation of said shaft said predetermined distance, means disposed above said first plate for stacking said workpieces along said axis of said passage with the lowermost workpiece in contact with said first plate, said plates being disposed on said shaft so as to cooperate with each other on rotation of said shaft to cause each said lowermost workpiece to be positioned consecutively in said passage; means to energize said work coil with a high frequency current; and means to control said energizing means in a predetermined manner with respect to said positioning means.

5. Apparatus for consecutively heat treating a plurality of workpieces by induction from a high frequency current, said apparatus comprising a work coil having a workpiece receiving passage; means for positioning workpieces in said passage in a consecutive manner, said positioning means including a fixture comprising an actuating shaft journaled by said fixture with its axis of rotation parallel to the axis of said workpiece receiving passage and spaced laterally therefrom a predetermined distance, means to rotate said shaft, a first circular plate disposed above said passage and fixedly attached to said shaft, a second circular plate disposed below said passage and fixedly attached to said shaft, each said plate having a circumferentially elongated opening disposed therein and spaced radially from said axis of rotation of said shaft for said predetermined distance, a guide tube disposed above said first plate for stacking said workpieces along said axis of said passage with the lowermost workpiece in contact with said first plate, said plates being disposed on said shaft so as to cooperate with each other on rotation of said shaft to cause each said lowermost workpiece to be positioned consecutively in said passage; means to energize said work coil with a high frequency current; and means to control said energizing means in a predetermined manner with respect to said positioning means.

6. Apparatus for consecutively heat treating a plurality of workpieces by induction from a high frequency

current, said apparatus comprising a work coil having a workpiece receiving passage; means for positioning workpieces in said passage in a consecutive manner, said positioning means including a fixture comprising an actuating shaft journaled by said fixture with its axis of rotation parallel to the axis of said workpiece receiving passage and spaced laterally therefrom a predetermined distance, means to rotate said shaft, a first circular plate disposed above said passage and fixedly attached to said shaft, each said plate having a circumferentially elongated opening disposed therein and spaced radially from said axis of rotation of said shaft for said predetermined distance, a guide tube disposed above said first plate for stacking said workpieces along said axis of said passage with the lowermost workpiece in contact with said first plate, said plates being disposed on said shaft so as to cooperate with each other on rotation of said shaft to cause each said lowermost workpiece to be positioned consecutively in said passage, and means to hold said workpieces in stacked position while said lowermost workpiece is being positioned in said passage; means to energize said work coil with a high frequency current; and means to control said energizing means in a predetermined manner with respect to said positioning means.

7. Apparatus for consecutively heat treating a plurality of workpieces by induction from a high frequency current, said apparatus comprising a work coil having a workpiece receiving passage; means for positioning workpieces in said passage in a consecutive manner, said positioning means including a fixture comprising an actuating shaft journaled in said fixture with its axis of rotation parallel to the axis of said workpiece receiving passage and spaced laterally therefrom a predetermined distance, means to rotate said shaft, a first circular plate disposed above said passage and fixedly attached to said shaft, a second circular plate disposed below said passage and fixedly attached to said shaft, each said plate having a circumferentially elongated opening disposed therein with its center spaced radially from said axis for said predetermined distance, means for stacking said workpieces along the axis of said passage above said first plate with the lowermost workpiece in contact with said first plate, said plates being positioned on said shaft with respect to each other so as to cooperate with each other on rotation of said shaft to cause each said lowermost workpiece to be positioned consecutively in said passage, means to hold said workpieces in stacked position while said lowermost workpiece is being positioned in said passage, and means to cause rotation of said workpiece positioned in said passage comprising an annular recess disposed in said second plate concentric with said shaft to form two radially spaced circular edges on the upper face of said second plate, the radius of one of said circular edges being at least equal to said predetermined distance; means to energize said work coil with a high frequency current; and means to control said energizing means in a predetermined relationship with said positioning means.

8. Apparatus for consecutively heat treating a plurality of workpieces by induction from a high frequency current, said apparatus comprising a work coil having a plurality of workpiece receiving passages; means for simultaneously positioning workpieces in said passages in a consecutive manner, said positioning means including a fixture comprising an actuating shaft suitably journaled in said fixture with its axis of rotation parallel to the axes of said work-

piece receiving passages and spaced laterally from one of said passages a predetermined distance, means to rotate said shaft, a first circular plate disposed above said passages and fixedly attached to said shaft, a second circular plate disposed below said passages and fixedly attached to said shaft, each said plate having a pair of radially spaced circumferentially elongated openings having radial widths sufficient to allow workpieces to pass through said openings unobstructed when said openings are aligned with said passages, means for stacking said workpieces along the axes of said passages above said first plate with the lowermost workpieces in contact with said first plate, said plates being positioned on said shaft with respect to each other so as to cooperate with each other on rotation of said shaft to cause said lowermost workpieces to be positioned in said passages, means to hold said workpieces in stacked position while said lowermost workpieces are being positioned in said passages, means to energize said work coil with a high frequency current; and means to control said energizing means in a predetermined relationship with said positioning means.

9. Apparatus for consecutively heat treating a plurality of workpieces by induction from a high frequency current, said apparatus comprising a work coil having a plurality of workpiece receiving passages; means for simultaneously positioning workpieces in said passages in a consecutive manner, said positioning means including a fixture comprising an actuating shaft suitably journaled in said fixture with its axis of rotation parallel to the axes of said workpiece receiving passages and spaced laterally from one of said passages a predetermined distance, means to rotate said shaft, a first circular plate disposed above said passages and fixedly attached to said shaft, a second circular plate disposed below said passages and fixedly attached to said shaft, each said plate having a pair of radially spaced circumferentially elongated openings having radial widths sufficient to allow workpieces to pass through said openings unobstructed when said openings are aligned with said passages, means for stacking said workpieces along the axes of said passages above said first plate with the lowermost workpieces in contact with said first plate, said plates being positioned on said shaft with respect to each other so as to cooperate with each other on rotation of said shaft to cause said lowermost workpieces to be positioned in said passages, means to hold said workpieces in stacked position while said lowermost workpieces are being positioned in said passages, and means to cause rotation of said workpieces positioned in said passages comprising annular recesses disposed in said second plate concentric with said shaft to form radially spaced circular edges on the upper face of said plate, said radially spacing of two of said edges being equal to the radial spacing of said elongated openings and the radius of one of said circular edges being equal to said predetermined distance; means to energize said work coil with a high frequency current; and means to control said energizing means in a predetermined relationship with said positioning means.
